UNITED STATES PATENT OFFICE.

THOMAS GUY BLOOD, OF BIRMINGHAM, ENGLAND.

DESIGN FOR A HOUSEMAID'S BOX.

55,023.

Specification for Design.

Patented May 4, 1920.

Application filed September 27, 1919. Serial No. 326,996. Term of patent 14 years.

To all whom it may concern:

Be it known that THOMAS GUY BLOOD, subject of the King of Great Britain, residing at Birmingham, England, have invented a new, original, and ornamental Design for a Housemaid's Box, of which the following is a specification, reference being had to the accompanying drawing, forming part thereof.

The figure is a perspective view of a housemaid's box, showing my new design.

What I claim as new and desire to secure by Letters Patent is:—

The ornamental design for a housemaid's box, as shown.

In testimony whereof I have hereunto set my hand in presence of two subscribing witnesses.

THOMAS GUY BLOOD.
